US00D667711S

(12) **United States Design Patent**
Walters

(10) **Patent No.:** **US D667,711 S**
(45) **Date of Patent:** **** Sep. 25, 2012**

(54) **FASTENING TOOL**

(75) Inventor: **Kyle Walters**, Chicago, IL (US)

(73) Assignee: **Arrow Fasterner Co., LLC**, Saddle Brook, NJ (US)

(**) Term: **14 Years**

(21) Appl. No.: **29/414,693**

(22) Filed: **Mar. 2, 2012**

(51) **LOC (9) Cl.** **19-02**

(52) **U.S. Cl.** **D8/49**

(58) **Field of Classification Search** D8/49,
D8/50, 61, 68, 69, 70; D19/72, 73, 65, 69;
D21/532; D24/145; 7/158, 160; 227/4,

(57) **CLAIM**

The ornamental design for a fastening tool, as shown and described.

DESCRIPTION

FIG. 1 is a perspective view thereof;
FIG. 2 is an alternative perspective view thereof;
FIG. 3 is a front elevational view thereof;
FIG. 4 is a rear elevational view thereof;
FIG. 5 is a right side elevational view thereof; the left side elevational view being a mirror image thereof; and,
FIG. 6 is a top plan view thereof.

The broken-line disclosure in the views represents portions of the article in which the claimed design is embodied, but which form no part of the claimed design.
